DAVID H. WILSON, OF PATERSON, NEW JERSEY.

SYSTEM OF ELECTRIC WELDING.

1,187,408.

Specification of Letters Patent. Patented June 13, 1916.

Application filed December 31, 1914, Serial No. 879,954. Renewed February 24, 1916. Serial No. 80,124.

To all whom it may concern.:

Be it known that I, DAVID H. WILSON, a citizen of the United States, and resident of Paterson, in the county of Passaic and 5 State of New Jersey, have invented certain new and useful Improvements in the System of Electric Welding, of which the following is a specification.

The object of my invention is a welding 10 system capable of giving a smooth weld by means of a steady current.

One of the features of my invention is a circuit-closer adapted to introduce a resistance into the welding circuit when the welding 15 terminals are brought into contact to prevent a too great flow of current, to reduce the resistance as the arc is drawn and thereafter to vary the resistance to compensate for variations of arc resistance due to 20 the unsteadiness of the operator's hand during welding.

In the drawings, the figure shows a diagram of the circuits and apparatus of my system.

25 From the one pole (preferably the positive) of the generator or other source of welding current 1 a circuit is first established by way of the conductor 2, high resistance 3, conductor 4, relay 5, conductor 6 to the operator's tool or terminal 7, preferably carrying the metal welding pencil 8 adapted to be brought into contact with the work 9 which may be any portion of fractured machinery or other metal adapted 30 to be operated upon by welding. The circuit is completed by way of conductor 10 to the other pole of the generator 1.

The contact of the terminals 8 and 9 permits enough current to pass to energize and 40 operate the relay 5 but not enough to permit the drawing of the arc. The relay lever armature 11 when attracted causes the bridge 12 to close the circuit between the contacts 13 thereby introducing the carbon 45 pile resistance 14 by way of the following circuit:—negative pole of the generator 1, conductor 2, conductor 15, solenoid 16, le-

ver 17, pile 14, contacts 13, conductor 18 to the pencil 8.

The moment that current traverses the 50 solenoid, the resistance of the pile, which is normally at its lowest point under the tension of the spring 19, is increased. This happens before the operator has time to start drawing his arc. As the arc is drawn 55 and its resistance increases, the lessened current in the solenoid weakens its force, and the spring 19 reduces the resistance of the pile to compensate for the increasing length of arc. Any variation of the arc due to the 60 unsteadiness of the operator's manipulation of his tool is thereafter compensated for by the solenoid and pile to render the current substantially uniform.

What I claim is:—

1. In a welding system, in combination, 65 a source of welding current, two terminals one of which is manually operable, and between which an arc is adapted to be drawn, means exterior to said circuit brought into 70 said circuit when said terminals are brought into contact, to prevent a too great flow of current across said terminals, and a circuit controller adapted to automatically raise the voltage across said terminals as the arc 75 resistance rises due to the separation of said terminals.

2. In a welding system, in combination, 80 a source of welding current, two terminals one of which is manually operable, and between which an arc is adapted to be drawn, means exterior to said circuit brought into 85 said circuit when said terminals are brought into contact, to prevent a too great flow of current across said terminals, a circuit controller adapted to automatically raise the voltage across said terminals as the arc resistance rises through the separation of said terminals, and means to automatically restore 90 said system to its original condition upon the rupture of said arc.

3. In a welding system, in combination, 95 a source of welding current, two terminals one of which is manually operable and be-

tween which an arc is adapted to be drawn, means normally exterior to said circuit brought into said circuit when said terminals are brought into contact, to prevent a too great flow of current across said terminals, and adapted to automatically raise the voltage across said terminals as the arc resistance rises through the separation of said terminals, and controlled by the current to

automatically maintain an even current and 10 to compensate for the variation of resistance in said arc.

Signed at New York in the county of New York and State of New York.

DAVID H. WILSON.
